UNITED STATES PATENT OFFICE.

WILLIAM R. PARK, OF TAUNTON, ASSIGNOR TO THE HANCOCK INSPIRATOR COMPANY, OF BOSTON, MASSACHUSETTS.

INJECTOR.

SPECIFICATION forming part of Letters Patent No. 298,884, dated May 20, 1884.

Application filed September 17, 1883. (Model.)

To all whom it may concern:-

Be it known that I, WILLIAM R. PARK, of Taunton, county of Bristol, State of Massachusetts, have invented an Improvement in 5 Injectors, of which the following description, in connection with the accompanying drawings, is a specification, like letters on the drawings representing like parts.

This invention, relating to an injector or apparatus for raising and forcing fluids by the action of a jet of steam or vapor, is embodied in an apparatus containing a nozzle for the admission of the actuating steam or vapor, a combining-tube and delivery-tube arranged 10 axially in line therewith, a space being left between the nozzle and the mouth of the combining-tube communicating with the water or fluid supply pipe. The combining-tube converges in the direction of the flow of the liquid 15 through it, and terminates in a short cylindrical passage, at the end of which the delivery-tube begins, the bore of which is conical, with its smallest diameter coincident with the end of the cylindrical passage.

20 The invention consists in the combination, with the said nozzle and combining and delivery tubes, of a movable controlling-spindle passing longitudinally therethrough, and provided with enlargements, cylindrical and conical, by which the effective relative area of the nozzle for the admission of the actuating steam or vapor and the throat in the cylindrical passage between the combining and delivery tubes may be governed, whereby the 25 instrument may be first made a lifting-jet apparatus, which shall cause water to rise from a well or other source of supply and pass through the combining and delivery tubes in the same quantity, per unit of time, as required 30 by the instrument when operating as a forcing apparatus, and the instrument then, by the manipulation of the said spindle, be converted into a forcing apparatus, and by the further manipulation of the spindle be adjusted to 35 deliver water in such quantity as may be desired.

The invention further consists in the combination, with said steam-nozzle, combining-tube, and delivery-tube, and controlling-spindle, of an overflow-cock located in a branch 40 from the pipe leading to the boiler between

the discharge end of the delivery-tube and the usual check-valve in said pipe; in supporting the said spindle in guides near the ends of the injector, whereby lateral motion of the spindle is prevented; and, further, in constructing the spindle in two parts and fastening them together within the instrument. 55

In this specification steam will be considered as the actuating-vapor and water as the fluid to be raised and forced, though it is obvious that any vapor which will be condensed by contact with the fluid raised or forced can be used in the place of steam, and any fluid which will condense the actuating-vapor can 60 be raised and forced thereby in this apparatus. For convenience of description, also, the apparatus will be considered as placed upright, with the steam-nozzle at the top, so that the flow of steam and water through the combining and delivery tubes shall be downward. 70

Injectors which are adapted to raise water from any considerable depth, as hitherto constructed, have had either a separate lifting-jet apparatus or ejector, the action of which is discontinued after the forcing-jet or injector proper is at work; or a separate lifting-jet apparatus communicating with and constantly supplying water to a forcing apparatus; or, a lifting-jet apparatus, which, after the water 75 has been raised and set running through the combining and delivery tubes to the atmosphere or waste, is convertible into a forcing apparatus or injector proper. 80

My invention is an improvement in the last-named class of instruments; and its object is to provide, in a single injector, a lifting apparatus which will raise water from as great a depth as can be done by any injector and deliver it in sufficient quantity, and which can 90 be easily converted into a forcing apparatus; and, further, to provide means for adjusting such forcing apparatus when in operation, so that it may act with steam of any desired pressure, and may be made to deliver a small or 95 large quantity of water at the will of the operator without impairing the certainty or efficiency of action of the apparatus. 85

Figure 1 is a longitudinal section of an injector embodying my invention, showing the apparatus arranged to raise water from a well or other source of supply; Fig. 2, a cross-

section thereof on the dotted line x x , Fig. 1; Fig. 3, a longitudinal section thereof with the controlling-spindle raised, showing the apparatus arranged to continue the flow of water from the well and to force it against a pressure greater than the initial pressure of the actuating-steam. Fig. 4 is a longitudinal section thereof, with the controlling-spindle raised to its highest point, the instrument then delivering its minimum quantity of water for any given steam-pressure.

The injector comprises the water-chamber a , having an inlet, 2, connected with the well or water-supply, and also having inlet and outlet openings 3 and 4, the former containing the steam-nozzle b , held in place between the shoulder 9 in the piece a and the end of the steam-inlet chamber c , which is screwed into the piece a , as shown, and provided with an inlet-passage, 6, connected with the source of the steam. The outlet-opening 4 of the water-chamber a has screwed into it a tube, d , within which is formed the tapering passage d' and cylindrical passage d'' (together forming the combining-tube) and the delivery-tube d^3 . The tube d is inserted through the opening 3 of the said chamber a before the parts b c are connected therewith. The casting of the water-chamber a has below the outlet 4 an internally-threaded portion, 5, into which a pipe, 10, is screwed. This pipe 10 surrounds the discharge end of the delivery-tube d^3 , and is designed to be connected to the boiler. In a branch of this pipe, below the injector, is placed a cock or overflow-valve, z , to afford a temporary outlet to the atmosphere, and beyond the branch is the usual check-valve.

The steam-nozzle b is arranged axially with the combining-tube d' d'' , and terminates at or near the mouth or inlet end thereof. The annular space between the steam-nozzle b and the internal bore of the mouth of the combining-tube d' forms a passage of constant area, through which water passes from the chamber a into the combining-tube d' d'' . The steam-nozzle b is provided with a tapering seat, b' v' , decreasing in diameter in the direction from the steam-chamber c toward the water-chamber a , and the bore of the said nozzle increases in diameter from the said seat, first, with an abrupt taper for a short distance, v' t' , and then with a less taper to the exit end of the nozzle. The upper portion of the combining-tube d' decreases in diameter from its mouth, (which is at or near the exit end of the steam-nozzle,), and terminates in the cylindrical passage d'' . The delivery-tube d^3 then begins, increases in diameter with a uniform taper, and continues to its exit end as a cylindrical tube. The passage of steam from the inlet-passage 6 and chamber c , through the steam-nozzle b , is first governed by the plug e , tapering reversely to the seat b' , and formed at the lower end of a cylindrical enlargement, f , upon a controlling-spindle, g g' , which passes axially through the steam-nozzle, the combining-tube and its cy-

lindrical passage d'' , and delivery-tube, and is guided by the guides h h' , the former fixed in chamber c , and the latter in a sleeve, i , surrounding the discharge end of the tube d , and screwed upon the threaded exterior thereof. The portion g of the controlling-spindle is screw-threaded to engage the interior thread of a nut, k , which is screwed into the end of the steam-chamber c . A handle, n , is attached to the stem m of the spindle, by rotating which the spindle is caused to move longitudinally in the apparatus. The nut k is provided with a stuffing-box for packing the stem m . When the controlling-spindle is in its lowest position, the plug e is seated on its seat b' v' , and the flow of the steam into the steam-nozzle is prevented. Below the plug e the controlling-spindle is cylindrical for a short distance, (designated by o), and is of a diameter slightly less than that of the smallest diameter of the inlet end of the steam-nozzle at v' . The length of the cylindrical portion o is such that the steam-jet shall remain determined by the area between o and v' until the plug e shall have been removed by the upward motion of the spindle far enough from its seat b' to admit all the steam required for the maximum capacity of the steam-nozzle. Below the cylinder o the controlling-spindle continues for a distance about equal to the length of the cylindrical passage d'' as a cylinder, p , but of less diameter than at o . At v it expands conically to a line at t , which has a diameter sufficiently less than the diameter of the steam-nozzle at t' to cause, when the controlling-spindle is raised until t is in the same plane with t' , as shown in Fig. 3, the area of the annular steam-jet thus formed to be the maximum area desired. The length of the conical portion v t is equal to that of the portion v' t' of the steam-nozzle, but the taper of v t is slightly greater than that of v' t' . The controlling-spindle is necked in, or slightly reduced in diameter, below the base of the conical portion v t , and then gradually expands to a cylinder of the same diameter as at t , and continues for a distance a little more than the length of the combining-tube to q , when it again expands, forming a cone, r , of about the same taper as the delivery-tube d^3 , and of the same length as that tube. The spindle then continues as a cylinder, s , for a distance equal to the length of the cylindrical portion d^4 of the delivery-tube d^3 , and terminates in a cylinder, which is supported in the guide h' , before described. As the enlargements f and s on the controlling-spindle are both of greater diameter than the opening in the steam-nozzle at v' , the said spindle cannot be inserted from either end, and it is therefore made in two parts, the part q and all above it being inserted through the chamber c , and the part r s through the discharge end of the delivery-tube d^3 , after which the two pieces are firmly connected together, as by the screw-thread at s .

The mode of operation of the injector is as follows: The controlling-spindle being in its

lowest position, so that the plug e is upon its seat b' , the operator first opens the overflow-cock z in the branch of the pipe 10, and turns the handle n , thereby removing the plug e from its seat, and permitting steam to flow through the steam-nozzle. The spindle will then be in the position shown in Fig. 1. In this position the effective area of the orifice in the steam-nozzle is determined by the relative diameter 5 of the cylindrical portion o of the controlling-spindle, and that of the steam-nozzle at v' . The annular orifice thus formed between o and v' should have an area sufficiently less than the area of the throat formed at d^5 , between 10 the tapering portion of the spindle at r and the exit end of the combining-tube, to constitute an effective lifting or ejector apparatus. The steam from the chamber c , issuing through the orifice at v' , expands as it passes to the 15 exit end of the steam-nozzle b , and then enters the combining-tube $d' d^2$, continues through it, the delivery-tube d^3 , into the pipe 10, and out at the overflow-cock z , and rapidly exhausts the air from the water-chamber and 20 the water-supply pipe, so that water rises from the well into the said water-chamber, and is caused to flow through the combining-tube $d' d^2$, the delivery-tube d^3 , the pipe 10, and out at the overflow-cock. The operation of the 25 instrument as a lifting apparatus will continue until the entire cylindrical portion o of the controlling-spindle is withdrawn from the plane v' of the smallest diameter of the steam-nozzle. When the flow of water in a solid 30 stream at the overflow-cock z is established, the operator continues to turn the handle n . The effective area of the steam-nozzle remains constant so long as the cylindrical portion o is in the plane of v' ; but the area of the throat 35 at d^5 is gradually diminished as the spindle rises, and consequently the velocity of the discharged water is increased. The spindle being raised farther, the portion o of the controlling-spindle passes above the plane of v' , 40 and the smaller cylindrical portion p of the spindle comes abreast v' , and the effective area of the steam-nozzle is gradually increased to its maximum. At the same time the tapering portion r of the spindle has been 45 drawn into the cylindrical passage d^2 , and the area of the throat at d^5 has been gradually diminished. The increased quantity of steam 50 now issuing through the steam-nozzle accelerates still more the velocity of the water discharged through the overflow. The effective 55 area of the steam-nozzle, being now determined by the orifice formed between v' and p , will remain constant and at its maximum until the line v on the controlling-spindle coincides 60 with the plane of v' , at which point the tapering portion r of the spindle will have so contracted the throat at d^5 that it will be of sufficiently less area than the area of the steam-nozzle at v' that the instrument will constitute 65 an effective forcing apparatus or injector proper. If, now, the overflow-cock be closed,

the discharged water will open the check-valve in the continuation of the pipe 10, and enter the boiler in a continuous stream. At this point—*i. e.*, when the line v on the controlling-spindle is in the same plane with v' , as shown in Fig. 3—the relative areas of the orifice at $v v'$ and that of the throat at d^5 are such that the instrument will perform its maximum duty as an injector—*i. e.*, it will deliver its maximum quantity of water to the boiler. The operator will now, by still further raising the spindle, diminish the effective area of the steam-nozzle, and at the same time proportionately diminish the area of the throat at d^5 until, 70 when the line t on the controlling-spindle comes into the plane of v' , as shown in Fig. 4, the smallest effective area of the steam-nozzle is attained, and likewise the smallest area of the throat at d^5 . The instrument will then perform its smallest duty—*i. e.*, it will deliver its minimum quantity of water to the boiler. This position of the instrument is shown in Fig. 4. Between the extreme positions shown in Fig. 3 and in Fig. 4 the operator can place 75 the controlling-spindle in different positions, so that the instrument shall deliver just the quantity of water desired. In all the positions between that which gives it its minimum capacity and that which gives it its maximum, 80 the relative effective area of the steam-nozzle and of the throat at d^5 remains constant, so that the single instrument may be made at will an instrument of small or large capacity, and at that without impairing its efficiency or 85 economy of action. In the working of the instrument the successive positions of the controlling-spindle may follow one another so quickly that the rise of the spindle shall be practically uninterrupted. By the time the 90 cylindrical portion o of the spindle has been drawn above the plane of v' the water will have risen from the well and will be discharging through the overflow-cock in a solid stream. The further turning of the handle n will accelerate 95 the flow of the discharged water, and when it has attained sufficient velocity to enable it to enter the boiler the operator will close the overflow-cock, and then can continue to turn the handle n until the controlling-spindle is brought to a point at which the instrument shall deliver the desired quantity of 100 water.

The positions of the spindle proper to secure any desired adjustment may be indicated by marks upon the spindle, and a pointer attached to the case to register therewith, or by any other convenient means.

It will be observed that this instrument, when operating as a lifting apparatus, affords 110 a throat at d^5 of much greater area than the throat at the same point when the tapering portion r of the spindle is drawn into the cylindrical passage d^2 of the combining-tube.

In single injectors as usually constructed 115 the lifting-jet is compelled to act through the same area of throat at the exit end of the com-

bining-tube as is used when the forcing-jet is in action. The raising of the water by the action of the lifting-jet is consequently performed much more slowly than in my injector, or, in which the area of the throat into which the lifting-jet issues is large enough to permit the passage of the water at the same quantity, per unit of time, that it will be driven through by the forcing-jet when performing its maximum duty.

The location of the overflow-cock in the branch 10, beyond the discharge end of the delivery-tube permits the combining and delivery tubes to be made continuous, so that there is no danger of breaking the jet near the throat d' , as would be the case were the overflow-passage formed at that point. The support afforded by the guides h to the controlling-spindle is of great advantage in insuring the constant working of the instrument, for unless the spindle be held rigidly against any lateral motion the annular current surrounding the spindle will be so disturbed by any jar received by the instrument as to stop its action.

The configuration of the interior surfaces of the steam-nozzle, and combining and delivery tubes may be changed from the specific forms herein described, provided proper relative changes on the contour of the controlling-spindle are made.

I am aware that a spindle has been heretofore used in injectors, passing through the steam-nozzle, combining-tube, and into the mouth of the delivery-tube; but such spindle is designed to be withdrawn from the mouth of the delivery-tube when the instrument is in operation as an injector. In this class of instruments, furthermore, the overflow-escape is located between the combining and delivery tubes instead of beyond the delivery-tube, as in my apparatus.

I claim--

1. In an injector, the combination, with a steam-nozzle, combining-tube, and delivery-tube, of a controlling-spindle movable longitudinally within such nozzle and tubes, and

having a contour relative to the interior surfaces of such nozzle and tubes, as described, whereby when the spindle is moved the area of the throat at the junction of the combining and delivery tubes is decreased in proportion as the area for the inlet of steam at the nozzle is increased, and vice versa, substantially as and for the purpose described. 55

2. In an injector, the combination, with a steam-nozzle, combining-tube, and delivery-tube, and a controlling-spindle movable longitudinally within such nozzle and tubes, of an overflow-cock located between the discharge end of the delivery-tube and the check-valve in the pipe leading to the boiler, substantially as described.

3. In an injector, the combination, with a steam-nozzle, combining-tube, and delivery-tube, of a controlling-spindle movable longitudinally within such nozzle and tubes, and a guide, h' , therefor, located at or near the lower end of the said spindle, whereby the latter is maintained in accurate concentric position within the injector, substantially as described. 65

4. In an injector, the combination, with a steam-nozzle, combining-tube, and delivery-tube, of a controlling-spindle of larger diameter near its ends than between said ends, made in two portions and fastened together within the injector, substantially as and for the purpose described. 75

5. In an injector, in combination with the steam-nozzle having an expanding bore, $v' t'$, 80 a combining-tube, and the delivery-tube d' , the controlling-spindle movable within said nozzle and tube, having the tapering enlargements v , t , and r , whereby the spindle may be adjusted to increase or decrease the quantity 85 of water forced, substantially as shown and described.

In testimony whereof I have signed my name to this specification in the presence of two subscribing witnesses.
